UNITED STATES PATENT OFFICE.

EDWIN NORTON, OF NEW YORK, N. Y.

BOTTLE-CAP.

SPECIFICATION forming part of Letters Patent No. 758,273, dated April 26, 1904.

Application filed December 14, 1903. Serial No. 186,011. (No model.)

To all whom it may concern:

Be it known that I, EDWIN NORTON, a citizen of the United States, residing in New York, in the county of New York and State of New York, have invented a new and useful Improvement in Bottle-Caps, of which the following is a specification.

My invention relates to improvements in bottle-caps or closures for bottles, jars, or other vessels.

The object of my invention is to provide a bottle cap or closure of a simple construction that will effect a safe and secure closure against high internal pressure and which at the same time may be easily and conveniently opened with the fingers, thus entirely dispensing with the customary wrenches, levers, keys, corkscrews, and other tools heretofore commonly used, and thus saving the expense incident thereto.

My invention consists in the means I employ to practically accomplish this object or result—that is to say, it consists, in connection with a bottle, jar, or other vessel having an external shoulder at its neck or mouth, of a compressible cork or sealing disk, a cork-holder disk, and a clamp-disk having a depending crimping-flange adapted to be compressed or bent under the shoulder on the bottle-neck and having an annular rim bearing upon the rim of the cork-holder disk to compress the annular rim portion of the cork or sealing disk against the top of the bottle-neck and provided at its top portion with an integral thumb-piece and a tongue leading from the thumb-piece to the outer edge of the rim of the clamping-disk and provided also with a tearing-strip extending from the tongue across the depending crimping-flange of the clamp-disk. The thumb-piece is preferably circular in form and of the full diameter of the clamping-disk less the narrow annular rim thereof, which gives the proper bearing upon the rims of the cork-holder disk and cork and sealing disk in compressing the same against the top of the bottle-neck. The thumb-piece is also preferably raised or embossed in shape to stiffen the same and afford a hollow or seat to receive the ball of the thumb or finger in grasping the same. As the tongue extends

across the annular rim of the clamp-disk and to the corner or beginning of the depending crimping-flange, in opening the bottle the tongue lifts with the thumb-piece itself without resistance and bends back until it is straight 55 with the tearing-strip extending across the depending crimping-flange, when a comparatively slight amount of force applied through the thumb-piece causes the tearing-strip to tear or separate along the weakened lines 60 across the crimping-flange by a peeling action and very easily. The clamping-disk being thus divided, by removal of the tearing-strip it is free to be removed from the bottle, and the bottle may thus be opened very easily and 65 conveniently without the use of any special wrench or tool of any kind. As in my invention the depending upright or vertical crimping-flange of the clamp-disk is simply scored or furnished with weakened lines at each edge 70 of the tearing-strip and as the crimping-flange is thus left continuous and solid throughout its whole circumference, the strength and holding power of the clamp-disk are maintained unimpaired, and a very safe and secure closure 75 is thus produced and one capable of withstanding the highest internal pressure ordinarily employed in bottled goods.

My invention also consists in the novel construction of parts and devices and in the novel 80 combinations of parts and devices herein shown or described.

In the accompanying drawings, forming a part of this specification, Figure 1 is a perspective view of the bottle cap or closure embodying my invention and having also a bottle-neck to which it is applied. Fig. 2 is a top or plan view; Fig. 3, a central vertical section; Fig. 4, a perspective view showing the thumb-piece and its connecting-tongue lifted and 85 ready for opening the bottle by tearing or separating the tearing-strip from the clamp-disk, and Fig. 5 is a detail perspective view of the cork-holder disk.

In the drawings, A represents a bottle, jar, 90 or other vessel having at its mouth or neck a cap-holder groove or shoulder a.

B is a sheet-metal cork-holder disk having preferably a narrow depending cork-retaining flange b for keeping or holding the cork 100

- or sealing disk C in place therein and for confining its edges from spreading, flowing, or thinning out when subjected to the pressure of the sealing operation. This flange *b* is 5 preferably substantially cylindrical or at right angles to the plane of the cork or sealing disk, and thus serves to hold the cork or sealing disk C in place without the necessity of any glue or paste.
- 10 D is the sheet-metal clamp-disk, the same having a continuous depending crimping-flange *d* extending around its whole circumference and adapted to be smoothly bent or crimped into or under the cap-holder groove 15 or shoulder *a* on the neck or mouth of the bottle, jar, or other vessel. The clamp-disk D has a flat annular rim *d'* at its top or disk portion, preferably about an eighth of an inch in width, to form a proper bearing against the 20 rim portion of the cork-holder disk B and interposed cork or sealing disk C in compressing the same against the top edge or face of the bottle-neck. The clamp-disk D has a thumb-piece *d''* at its top or disk portion separated from the annular rim *d'* by a circular slit or cut *d³* and a tongue *d⁴* extending across the rim *d'* and separated therefrom by parallel slits or cuts *d⁵* and which tongue terminates in a tearing-strip *d⁶*, marked off by 25 parallel scores or weakened lines *d⁷* and extending across the depending crimping-flange *d* of the clamp-disk D. The thumb-piece *d''* preferably has a raised or embossed portion *d⁸* to form a hollow or seat for the ball of the 30 thumb in grasping the same. The raised or embossed shape of the thumb-piece also stiffens the same, and thus causes it to act more efficiently as a means for removing the tearing-strip and opening the bottle.
- 35 The scores or weakened lines 77 of the tearing-strip preferably terminate just above the point where the crimping-flange bends under the shoulder *a* of the bottle-neck, so that there will be no danger of the crimping operation 40 breaking the crimping-flange.
- 45 To open a bottle, jar, or other vessel provided with my bottle cap or closure, all that is required is simply to raise the thumb-piece by means of one's thumb or finger nail and 50 then grasp it between the thumb and finger and bend the tongue back upon itself and tear or remove the tearing-strip from the clamp-disk D, thus allowing the clamp-disk to spread open and off the bottle. All special wrenches, 55 keys, or other tools for opening the bottle are thus by my invention entirely dispensed with.
- I claim—
- 60 1. The combination with a bottle, jar or other vessel having an external shoulder at its neck or mouth, of a cork or sealing disk, a cork-holder disk and a clamp-disk having a 65 depending crimping-flange solid and continuous throughout its whole circumference and a flat annular bearing-rim, and provided with an integral thumb-piece, a tongue extending

across the annular bearing-rim and a tearing-strip marked off by scores or weakened lines extending across the depending crimping-flange and adapted to be separated by tearing along said scores or weakened lines by force applied through the thumb-piece, substantially as specified.

2. In a closure for bottles, jars or other vessels, the combination with a cork or sealing disk, of a clamp-disk having a depending crimping-flange solid and continuous throughout its whole circumference and an annular bearing-rim and provided with a tearing-strip marked off by weakened lines and extending across the crimping-flange, a thumb-piece separated from said annular rim by a curved slit or cut and a tongue extending across the bearing-rim and uniting the thumb-piece and tearing-strip, said tearing-strip being adapted to be removed by tearing along its marginal 85 weakened lines by force applied through the thumb-piece.

3. In a closure for bottles, jars or other vessels, the combination with a cork or sealing disk, of a cork-holder disk and a clamp-disk having a depending crimping-flange solid and continuous throughout its whole circumference, an annular bearing-rim, and provided with a central circular thumb-piece, a tongue extending across the bearing-rim, and a tearing-strip extending across the crimping-flange and adapted to be separated by tearing along said scores or weakened lines by force applied through the thumb-piece, substantially as specified.

4. In a closure for bottles, jars or other vessels, the combination with a cork or sealing disk, of a cork-holder disk and a clamp-disk having a depending crimping-flange, an annular bearing-rim, and provided with a central circular thumb-piece, a tongue extending across the bearing-rim, and a tearing-strip extending across the crimping-flange, said thumb-piece having a raised or embossed central portion to stiffen the same and form a seat for the finger or thumb in grasping the same, substantially as specified.

5. In a closure for bottles, jars or other vessels, a clamp-disk having a depending crimping-flange solid and continuous throughout its whole circumference, an annular bearing-rim, a tearing-strip extending across the crimping-flange, a tongue extending across the bearing-rim, and a central thumb-piece inside the bearing-rim, said tearing-strip being adapted to be removed by tearing along its marginal weakened lines by force applied through the thumb-piece, substantially as specified.

6. In a closure for bottles, jars or other vessels, a clamp-disk having a depending crimping-flange solid and continuous throughout its whole circumference, an annular bearing-rim, a tearing-strip extending across the crimping-flange, a tongue extending across the bearing-rim, and a central thumb-piece inside the

bearing-rim, said clamp-disk having a circular slit or cut around the thumb-piece, parallel slits or cuts at the edges of the tongue and scores or weakened lines bounding the tearing-strip, said tearing-strip being adapted to be removed by tearing along its marginal weakened lines by force applied through the thumb-piece, substantially as specified.

7. In a closure for bottles, jars or other vessels, a clamp-disk having a depending crimping-flange solid and continuous throughout its whole circumference, an annular bearing-rim, a tearing-strip extending across the crimping-flange and a thumb-piece inside the bearing-
15 rim for removing the tearing-strip, said tearing-strip being adapted to be removed by tearing along its marginal weakened lines by force applied through the thumb-piece, substantially as specified.

8. In a closure for bottles, jars or other vessels, a clamp-disk having a depending crimping-flange solid and continuous throughout its whole circumference, an annular bearing-rim, a tearing-strip extending across the crimping-flange and a thumb-piece inside the bearing-
20 rim for removing the tearing-strip, the scores or weakened lines of the tearing-strip terminating at or near the point where the crimping-flange bends under the shoulder of the bottle-neck, said tearing-strip being adapted
25 to be removed by tearing along its marginal weakened lines by force applied through the thumb-piece, substantially as specified.
